COSTUME JEWELRY

Mario Lely, New York, N. Y.

Application March 9, 1935, Serial No. 10,236

4 Claims. (Cl. 63—20)

This invention relates to costume jewelry and has for an object the provision of an improved self-attaching clip which is so constructed as to be either inherently of an ornamental nature or 5 to serve as an attaching clip for an ornament supported thereby.

The invention broadly comprehends a contractile helical clip body of any desired configuration in which adjacent convolutions thereof are adapted 10 to be separated to receive and clamp therebetween the article to be decorated thereby.

The invention in one of its forms consists of a coiled contractile body fashioned from a length of resilient wire, strung with beads or otherwise 15 ornamented and having an enlarged knob or equivalent ornamental element at either one or both of its ends.

The invention further provides an improved 20 article of the indicated character which includes a resilient body having coiled contractile opposite end portions, the adjacent convolutions of which end portions are adapted to clamp therebetween the article decorated thereby.

The invention further resides in the provision 25 of an improved article of costume jewelry which is comparatively simple in its construction, economical to produce, capable of a wide variation of designs, which may be applied and removed with the greatest facility and which effectively retains 30 itself in attached position against accidental or unintentional displacement.

With the above enumerated and other objects in view reference is now made to the following 35 specification and accompanying drawing in which there has been set forth several preferred embodiments of the invention, while the appended claims cover variations and modifications thereof falling within the scope of the invention.

In the drawing:

40 Fig. 1 is a perspective view of a piece of costume jewelry constructed in accordance with the invention and illustrating the same applied to a hat for decorating the same.

Fig. 2 is a front view of the ornament on an 45 enlarged scale.

Fig. 3 is a side view of the same in applied position.

Fig. 4 is a perspective view of a modified form of the invention.

50 Referring to the drawing by characters of reference and particularly to the form of the invention illustrated in Figs. 1, 2 and 3, the article consists of a coiled contractile body A preferably constructed of a length of resilient wire 10 upon which is strung beads 11 or equivalent ornamental elements which are arranged thereon throughout the length of the body. The 55 opposite ends of the body have attached thereto

knobs 12 and 13 or equivalent ornamental elements for obtaining a decorative effect and for retaining the beads or elements 11 on the body. In practice the end elements 12 and 13 may be attached to the wire in any desired manner such as by a threaded connection 14 so that the knobs or elements 12 and 13 may be removed if desired to vary the character of the ornamental elements 11.

In the form of the invention shown in Figs. 1 10 to 3 inclusive, the knob or end element 12 is shown arranged so as to be disposed concentrically within the confines of the area encompassed by the coiled body A, while the knob or element 13 is disposed beyond the confines of said coiled 15 body.

In the form of the invention shown in Fig. 4, the body consists of a length of resilient wire 15 having coiled contractile end portions 16 and 17, the terminals of which are provided with knobs 20 18 or equivalent decorative elements. In this form of the invention, an ornament 19 is secured to the wire 15 intermediate the coiled end portions, adjacent convolutions of which coiled end portions 16 and 17 may be utilized to clamp there- 25 between adjacent portions of the costume such as a dress, scarf, collar or the like.

What is claimed is:

1. A costume ornament including a resilient 30 coiled contractile body, adjacent convolutions of which are adapted to clamp therebetween the article to be decorated thereby, ornamental elements at opposite ends of the body, one lying within the confines of said body and the other disposed beyond the confines thereof, and beads 35 strung upon said body between said end elements.

2. A costume ornament including a body consisting of a length of resilient wire having coiled contractile end portions, adjacent convolutions of each of which end portions are arranged in 40 different planes and adapted to clamp therebetween the article to be decorated thereby, and decorative means secured to said body intermediate the ends thereof.

3. A costume ornament including a resilient 45 coiled contractile body, adjacent convolutions of which are adapted to clamp therebetween the article to be decorated thereby, and decorative elements strung upon said body throughout its length.

4. A costume ornament including a resilient 50 coiled contractile body, adjacent convolutions of which are adapted to clamp therebetween the article to be decorated thereby, decorative elements strung upon said body throughout its 55 length, and means for retaining said elements on the body.

MARIO LELY.
